11 Claims

ABSTRACT OF THE DISCLOSURE

The novelty item comprises a simulated winding key, of enlarged proportions, which may be applied to the coat or other garment of a person so as to effect the illusion that such person is a mechanized manikin. The key motion is controlled by a concealed electric switch in the hand of the person; also, the device includes novel mounting means completely concealed, for exhibiting the winding key in such manner as to create the illusion that said key projects directly from the flesh of the wearer.

This invention relates to a novelty item and more particularly to an attention arresting device which may be remotely actuated for producing unusual and attention-arresting effects.

An object of the invention is to provide an attention-arresting item in the form of an enlarged keywinder which is adapted to be mounted to the clothing of a person in such a manner as to, by way of example, project therefrom in such a manner as to give the effect of a manikin being wound or unwound upon actuation of the winder.

A further object of the invention is to provide a device having the hereinabove characteristics and which includes an attention-arresting element and base therefor which are adapted to be securely though releasably associated with the clothing and/or suitcoat of an individual by reason of a cooperating relationship with a support member on an opposite side of the suitcoat whereby the device may be quickly and easily associated with and/or removed from an article of clothing without damage thereto.

Still another object of the invention is to provide actuating means in the form of an electric motor completely housed within an elongate central portion of the attention-arresting element and motor control means including a switch and battery remote therefrom in the form of a pocket-receptive control unit.

Still a further object of the invention is to provide a device having the hereinabove characteristics which is constructed in such a manner as to withstand the normal use and abuse to which such items are subjected.

These and other objects are attained by the means described herein and as disclosed in the accompanying drawings in which:

FIG. 1 is a perspective view of the subject device as it would appear in use when secured to the suitcoat of a person.

FIG. 2 is an enlarged view, partly in section of the attention-arresting element and base of the device.

FIG. 3 is a plan view looking down onto FIG. 2.

FIG. 4 is a plan view looking upwardly at FIG. 2.

FIG. 5 is a plan view of a support member comprising a detail of the invention.

FIG. 6 is a longitudinal, vertical, sectional view of the device of FIG. 5.

FIG. 7 is an exploded view illustrating the manner in which the base and support member are coupled incident to providing the device of FIG. 1.

FIG. 8 is a schematic illustration of a combination

2

battery holder and switch element comprising a detail of the invention.

With particular reference now to FIG. 2 the numeral 10 denotes a rotatable, attention-arresting element which, in the preferred embodiment of the invention is made to simulate an oversized keywinder comprising a pair of duplicate complementary wing portions 12 and 14, each of which is secured to and carried by an elongate hollow central portion 16 which, in the preferred embodiment of the invention may comprise a cylindrical tube open at its lower end and closed at its upper end as at 18.

The numeral 20 denotes a base for the rotatable, attention-arresting element 10, and said base includes structural elements 22 which define a series of compartments such as, by way of example A, B, C, D, and E in which various components of the driving mechanism are housed.

By way of example, electric motor 30 is suitably housed within compartment E wherein bearings 32 and 34 project through and are received in suitable openings provided in transverse elements 36 and 38 respectively which collectively define compartment E.

A rotary motion is imparted to drive shaft 40 by reason of the gear train illustrated within compartment D wherein gear 42 is secured to and carried by the drive shaft of motor 30 and wherein gear 44 is secured to and carried by the lower end of drive shaft 40. The numeral 51 denotes a length of resilient tubing which provides a slip-clutch connection between drive shaft 40 and drive shaft element 50, the upper end of which element 50 terminates in a friction member 52 received within a complementary socket provided in an internal boss 54 of the upper closed end 18 of central portion 16 of element 10.

In the preferred embodiment of the invention, pairs of elongate elements 60 and 70 project from base 20 along with a central element 80, as best illustrated in FIGS. 2, 4 and 7, wherein elongate elements 60—60 are in electrical connection with one side of motor 30 and wherein elements 70—70 are in electrical contact with the other side of said motor. The elongate elements 60, 70 and 80 terminate in sharpened piercing points or prongs for facilitating their respective introduction into and through one or more layers of a supporting fabric or panel denoted by the letter Q, FIGS. 1 and 7.

With particular reference to FIGS. 5, 6 and 7, the numeral 90 denotes generally a support member which includes a base portion 92 and an upwardly extending body portion 94. The base portion is provided with pairs of sockets 72—72 which are electrically interconnected as by conductor 74; pairs of sockets 62—62 which are interconnected by conductor 64; and a single, centrally disposed socket 100.

Sockets 62—62 are adapted to frictionally receive elongate elements 60—60 and sockets 72—72 are adapted to frictionally receive elongate elements 70—70 for establishing a good electrical contact between said elongate elements and their respective sockets. Socket 100 is adapted to receive elongate element 80 which, unlike the other elongate elements is preferably provided with external threading to be engaged by a nut 82 for thereby releasably securing the base and attention-arresting element relative to the support member.

With particular reference to FIG. 8, the numeral 110 denotes generally a compact housing dimensioned to receive a plurality of dry cells 112, 114 and 116 in series relationship. A manually operable switch lever 120 is provided for enabling an operator to establish an electrical contact between contacts 122 and 124 for placing motor 30 in series circuit with the batteries via conductors 126 and 128 which are suitably housed within a flexible conduit 130 of such a length as to extend from a pocket of the wearer to the support member when mounted as in FIG. 1.

From the foregoing it will be apparent that whenever an electric circuit is closed to motor 30 the attention-arresting element 10 will rotate thereby providing a startling, interesting and unique attention-arresting effect. In passing it should be noted that sockets 62—62 and 72—72 are disposed in such a manner as to alternatively receive elongate elements 60—60 and/or 70—70, it being noted that the only difference in operation is that the attention-arresting member will rotate in an opposite direction.

The attention-arresting member 10, including the elongate central portion 16 may be quickly disassociated from the drive mechanism by removing screw 19 which precludes accidental or unintentional disengagement of friction member 52 from the socket of boss 54.

With particular reference to FIGS. 4 and 7 it will be noted that the base includes flat, axial surface S from which the elongate elements 60, 70 and 80 project; and as illustrated in FIGS. 5 and 7 the support member 90 includes a flat, axial surface T in or through which the various sockets are provided.

When the various elongate elements have been fully received in their respective sockets and nut 82 secured onto member 80 the length of portion 94 is effective to provide such anchorage of the device as to permit the wearer thereof to freely move about, bend over, etc.

From the foregoing it will be observed that I have thus provided a simple, yet highly effective attention-arresting device which may be conveniently associated with an article of wearing apparel without damage to same.

It should be understood that various changes and modifications may be made within the structural details of the device within the scope of the appended claims without departing from the spirit of the invention.

What is claimed is:

1. In combination a garment and a novelty item attached thereto:

- (a) a rotatable attention-arresting element,
- (b) a stationary base for said element,
- (c) a stationary support member for said base,
- (d) means mounting said element for rotation relative to said base, the improvement thereof comprises,
- (e) means releasably mounting said base upon said support member, with the fabric or the garment disposed between said base and said support member,
- (f) motor means secured to and carried by said base and in driving relationship with said rotatable element, and
- (g) manually operable motor control means remote from said motor means, including a source of electric current in circuit with said motor means.

2. A novelty device as called for in claim 1 wherein the attention-arresting element includes an elongate central portion which conceals and completely houses said motor means.

3. The device as called for in claim 1 wherein the motor means constitutes an electric motor and wherein said motor control means includes a battery receptive housing enclosing a manually operable switch.

4. A device as called for in claim 1 wherein said attention-arresting element is shaped to simulate an oversized keywinder.

5. A device as called for in claim 1 wherein a slip

clutch is interposed between the said motor means and rotatable element.

5. The device as called for in claim 1, wherein said releasable mounting means includes elongate slender prongs formed of electrically conductive material, said prongs being electrically connected in the circuit with said motor means and said motor control means.

10 6. The device as called for in claim 1, wherein the stationary support member is enlarged in area to abut an extensive area of the inside of a garment, thereby to minimize sagging of the attention-arresting element exteriorly of the garment.

15 7. The device as called for in claim 1, wherein the attention-arresting element includes an axially disposed tube encasing said stationary base.

8. The device as called for in claim 1, wherein said attention-arresting element includes an axially disposed tube encasing said stationary base.

9. The device as called for in claim 1, wherein said

releasable mounting means includes a plurality of elongate slender prongs to penetrate the fabric of the garment aforesaid.

20 10. A device as called for in claim 9 wherein the base includes an axial surface from which a plurality of said elongate prongs project; the support member includes an axial surface having a plurality of sockets therein; and means for securing the base relative to said support member with the said elongate prongs each in a socket of said support member.

11. A device as called for in claim 9 wherein:

- (a) the base includes an axial surface from which a plurality of said elongate prongs project, and wherein each of said prongs terminate in piercing points for facilitating the introduction of each of said elements through one or more layers of fabric or the like;
- (b) said support member includes an axial surface having a plurality of sockets therein, one for receiving each of the aforesaid elongate prongs,
- (c) said motor means constitutes an electric motor in series circuit with certain of said elongate prongs,
- (d) said motor control means includes a battery receptive housing with a manually operable switch in series circuit with certain of the sockets of the support member,
- (e) said means for releasably securing said base to said support member constitutes one of the said elongate prongs which is dimensioned to project completely through one of the sockets of the support member to receive a retaining member for disposing and securing the axial surfaces of said base and supporting members on opposite sides of the fabric or the like through which the said elongate prongs project.
